UNITED STATES PATENT OFFICE.

BOY V. WOODWORTH, OF ST. LOUIS, MISSOURI, ASSIGNOR TO WESTERN SUPPLIES COMPANY, OF ST. LOUIS, MISSOURI, A CORPORATION OF MISSOURI.

MARKING AND CEMENTING MACHINE.

Application filed March 28, 1927. Serial No. 178,968.

This invention relates to marking and cementing machines which are capable of operation to perform the double function of marking one of the parts which are to be adhesively bonded to indicate the position of the other part, and to apply an adhesive substance to the marked part preparatory to the adhesive connection of the other part thereto.

10 An object of the invention is to provide a machine which may be conveniently and rapidly operated to outline upon one part the position to which another part is to be applied thereto and, at the same time, to apply 15 an adhesive substance within the marked area so that the work may be completed by applying the other part upon the marked area with sufficient pressure to cause a permanent adhesive connection.

20 Other objects will appear from the following description, reference being made to the drawing, in which,

Fig. 1 is a sectional view of the upper portion of the machine embodying the present invention.

Fig. 2 is an inverted plan view of one of the dies capable of use in this machine.

Fig. 3 is a cross sectional view on the line 3—3 of Fig. 2, the adhesive applying projections being shown in elevation.

Fig. 4 is a detail view of the die clamping device.

The invention shown is designed and adapted for cooperative use in and with a machine of the type disclosed in my copending application for marking machine, filed June 26, 1926, Serial No. 118,665. The invention is designed and adapted to be operatively mounted upon any appropriate form of support such as the frame 1, which is of sufficient height to support the mechanism at a proper height for convenient operation. The machine comprises a base which, in the form shown, includes a die supporting portion 2 at the front, and an adhesive and marking substance supporting portion 3 at the rear. As shown, the means for applying an adhesive and marking substance to the work comprises a pan or tray 4 designed and arranged to contain a quantity of adhesive substance and secured to the part 3 of the machine by screws 5.

The work locating and supporting devices are interchangeable and removable from the

machine, so that materials or work cut to different shapes and dimensions may be located by the use of an appropriate specially designed locating device. Each such locating device, one of which is shown, comprises a plate 6 having on its upper side forms 7 to receive marginal or projecting portions of the materials or work upon which the marked and cemented areas are to be provided. Each of said plates 6 is provided with a number of holes arranged to receive pins 8 extending from the supporting part 2 and thus hold the plate 6 immovable in proper location.

The die carrier comprises a frame 9 swingingly supported by a pair of front arms 10, the upper ends of which are pivoted to the lateral sides of the die carrier and the lower ends of which are connected to the part 2 by pivots 11, and a pair of rear arms 12 having their upper ends pivoted to the die carrier 9 and their lower ends attached to a rock shaft 13 extending across the machine below the pan 4. A handle 14 is connected with the die carrier 9 by a stem 15 and a die lock or clamp arm 16. The stem 15 passes through the die carrier 9 and is anchored in the handle whereby the die lock or clamp arm 16 may be turned by the handle 14. The die lock or clamp arm 16 is within a recess 17 in the underside of the die carrier 85 and is operative by the handle 14 to engage and secure the die plate to the die carrier. The extent of turning movement of the handle 14 is limited by a disc 18 attached to the handle and provided with a notch in one edge into which a pin 19 extends. The pin 19 is rigid with the die carrier and the notch in the plate 18 is of sufficient length to permit the handle 14 and the clamp or lock 16 to be turned approximately one-fourth of a revolution.

This machine is arranged to receive die plates having marking means of different designs adapted to mark the materials or work on the gage plate and to apply adhesive substance in the marked area. One such marker and adhesive applicator 20 is shown and is provided with a pair of spaced projections 21 approximately midway between its edges (Fig. 1) and arranged to extend upwardly into the recess 17 so that the ends of the die lock or clamp arm 16 may engage under the projections 21 and secure the die

plate to the carrier. Each die plate 20 has a number of upwardly projecting lugs 22 spaced from the projections 21 (Fig. 3) and arranged to engage in holes in the die carrier 5 to locate the die plates properly and to cooperate with the lock or clamp arm 16 to hold the die plates rigid on the carrier. The edges 23 (Fig. 4) of the die lock or clamp arm 16 are beveled, so that they readily pass 10 under the projections 21 and, by further turning movement of said arm, will clamp the die plate firmly in connection with the carrier.

The marker and adhesive applicator is attached to the underside of the plate 20, one such applicator being shown in plan view in Fig. 2 and in section in Fig. 3. While the designs and forms of these markers and applicators may be varied optionally, the 15 one shown comprises a flange 24 which is tapered in cross section (Fig. 3), and which approximately defines a crescent-shaped area (Fig. 2). Within the area defined by the flange 24 are numerous tapered projections 25 whose ends are in the same plane as the edge of the flange 24, and which are disposed in such relationship that they will pick up the adhesive substance from the pan 4 and carry and apply it to the materials 20 or work upon the plate 6.

As shown in Fig. 2, the area defined or enclosed within the flange 24 may be further subdivided as by an approximately circular flange 26 forming an enclosed area in which 35 there are an appropriate number of projections 27. The flange 26 and projections 27 have their edges and ends respectively in the same plane as the flange 24 and the projections 25.

40 In operation, the material or work upon which areas are to be marked and within which marked areas the adhesive substance is to be applied is placed upon the plate 6 and properly located by the forms 7. The 45 die carrier is then swung rearwardly and downwardly, causing the parts 24, 25, 26 and 27 to contact with the adhesive substance in the pan 4. A quantity of this adhesive substance adheres to said parts 24, 25, 50 26 and 27. The die carrier is then swung forwardly and downwardly to press the ends and edges of the parts 24, 25, 26 and 27 upon the material or work held in proper location by the forms 7. The adhesive substance 55 is thereby withdrawn from the marker and adhesive applicator and deposited upon the work or material. The adhesive substance deposited by the flange 24 and by the flange 26, if the same be present, defines marked areas upon the work or material, 60 within which marked area a sufficient quantity of adhesive substance is deposited by the projections 25 and 27. Next, the other piece of work or material which is to be 65 bonded to the one marked and provided with

adhesive substance aforesaid, is placed upon the marked area in proper position and, under proper pressure, becomes adhesively united. These operations may be carried on rapidly and easily so that the parts may be 70 adhesively united in proper relationship with the exercise of great care and by unskilled operatives.

The construction and arrangement of the machine may be varied within equivalent 75 limits without departure from the nature and principle of the invention as defined by the appended claims.

I claim:

1. In a machine of the character described, 80 a carrier frame, means for supporting said frame for swinging movements, a handle for swinging said frame, a device holding said handle in connection with said frame and permitting turning movements of said 85 handle, a plate, projections from said plate, a clamping element operated by said handle for engaging and releasing said projections, and devices cooperating with said clamping element to hold said plate in rigid connection with said frame. 90

2. A marker device comprising a plate, a pair of engageable spaced angular projections extending from one side of said plate for engagement with a support, and devices 95 spaced from said projections and cooperating with said projections to hold said plate from turning on the support.

3. A marking device comprising a plate, 100 angular projections extending toward each other from one side of said plate for engagement by an operating device, and projections in connection with said plate for holding the plate from turning.

4. A marker device comprising a plate, 105 a pair of spaced angular projections extending toward each other from one side of said plate for engagement with a support, and projections extending from the same side of said plate as said first-named projections for 110 engaging a support to prevent said plate from turning.

5. In a machine of the character described, 115 a swinging carrier frame, a handle for swinging said frame, a device holding said handle in connection with said frame and permitting turning movements of said handle, a plate, projections from one side of said plate, a clamping element operated by said handle for engaging and releasing said 120 projections, and an additional projection in connection with said plate for engaging said frame to hold said plate from turning.

6. In a machine of the character described, 125 a swinging carrier element, a die element, a projection on one of said elements for engaging the other to hold said die element from turning relative to said carrier element, a handle for swinging said carrier element, a device holding said handle in connection 130

with said carrier element and permitting turning movements of said handle, and a clamping device operated by said handle for engaging and releasing said projections.

5 7. In a machine of the character described, a swinging carrier element, a die element, a pair of spaced angular projections extending toward each other from one side of one of said elements, clamping means supported 10 by the other one of said elements, and a device for operating said clamping means to engage and release said projections.

8. In a machine of the character described, a swinging carrier element having a recess in its under side, a die element, projections on said die, element extending in said recess when said die element is in connection with said carrier element, a clamping device supported by said carrier element 20 in said recess, and means for operating said clamping device to engage and release said projections.

9. In a machine of the character described, a swinging carrier element having a recess in its underside, a die element, projections on said die element extending in said recess when said die element is in connection with said carrier element, a clamping device supported by said carrier element in said recess, means for operating said clamping device to engage and release said projections, and means carried by one of said elements for engaging the other and cooperating with said projections and said clamping

device to hold said die element from turning 35 on said carrier element.

10. A marker device comprising a plate, a pair of spaced angular projections extending toward each other from one side of said plate and approximately midway between 40 its edges for engagement with a support, means for cooperating with said projections to hold said plate from turning on the support, and marking means in connection with the other side of said plate from said projections. 45

11. A marker device comprising a plate, means projecting from near the center of one side of said plate for engaging a support to support the plate, and a number of 50 projections projecting from the same side of said plate and spaced from said means for engaging the support to prevent the plate from turning relative to the support during the time that said plate is supported by 55 said means.

12. In a machine of the character described, a swinging carrier element, a die element, means projecting from near the center of one side of said die element, a device supported by the carrier element for engaging said means to support said die element, and projections on one of said elements spaced from said means for engaging the other element to prevent said die element from 60 turning. 65

with said carrier element and permitting turning movements of said handle, and a clamping device operated by said handle for engaging and releasing said projections.

5 7. In a machine of the character described, a swinging carrier element, a die element, a pair of spaced angular projections extending toward each other from one side of one of said elements, clamping means supported 10 by the other one of said elements, and a device for operating said clamping means to engage and release said projections.

8. In a machine of the character described, a swinging carrier element having a recess in its under side, a die element, projections on said die, element extending in said recess when said die element is in connection with said carrier element, a clamping device supported by said carrier element 20 in said recess, and means for operating said clamping device to engage and release said projections.

9. In a machine of the character described, a swinging carrier element having a recess in its underside, a die element, projections on said die element extending in said recess when said die element is in connection with said carrier element, a clamping device supported by said carrier element in said recess, means for operating said clamping device to engage and release said projections, and means carried by one of said elements for engaging the other and cooperating with said projections and said clamping

device to hold said die element from turning 35 on said carrier element.

10. A marker device comprising a plate, a pair of spaced angular projections extending toward each other from one side of said plate and approximately midway between 40 its edges for engagement with a support, means for cooperating with said projections to hold said plate from turning on the support, and marking means in connection with the other side of said plate from said projections. 45

11. A marker device comprising a plate, means projecting from near the center of one side of said plate for engaging a support to support the plate, and a number of 50 projections projecting from the same side of said plate and spaced from said means for engaging the support to prevent the plate from turning relative to the support during the time that said plate is supported by 55 said means.

12. In a machine of the character described, a swinging carrier element, a die element, means projecting from near the center of one side of said die element, a device supported by the carrier element for engaging said means to support said die element, and projections on one of said elements spaced from said means for engaging the other element to prevent said die element from 60 turning. 65
